DESIGN FOR A BOX OR SIMILAR CONTAINER

Isador Silverman, Cleveland, Ohio, assignor to
The Forest City Rubber Company, Cleveland,
Ohio, a corporation of Ohio

Application March 29, 1937, Serial No. 68,450

Term of patent 14 years

To all whom it may concern:

Be it known that I, Isador Silverman, a citizen of the United States, residing at Cleveland, in the county of Cuyahoga and State of Ohio, have invented a new, original, and ornamental Design for a Box or Similar Container, of which the following is a specification, reference being had to the accompanying drawing, forming a part thereof, in which:

Fig. 2 is a side elevational view of a container embodying my new design; and

Fig. 3 is a section on the line 3—3 of Fig. 1.

The drawing is lined to indicate a gray background band at the top for the figures shown, a black band at the bottom, a white central band, a narrow red band between the white and gray bands, and a broad red band between the white and black bands. The appearance of the sides of the box or container not shown is the same as that of the sides illustrated in the drawing.

I claim:

The ornamental design for a box or similar container substantially as shown and described.

ISADOR SILVERMAN.
